(57) CLAIM

The ornamental design for a cheese server, as shown and described.

DESCRIPTION

FIG. 1 is a top perspective view of the cheese server showing
my new design;
FIG. 2 is a top plan view thereof;
FIG. 3 is a bottom plan view thereof;
FIG. 4 is a front elevation view thereof;
FIG. 5 is a rear elevation view thereof;
FIG. 6 is a left side elevation view thereof, the opposite side
being a mirror image thereof;
FIG. 7 is a top perspective view of a variation thereof;
FIG. 8 is a top plan view of FIG. 7;
FIG. 9 is a bottom plan view of FIG. 7;
FIG. 10 is a front elevation view of FIG. 7;
FIG. 11 is a rear elevation view of FIG. 7; and,
FIG. 12 is a left side elevation view of FIG. 7, the opposite side being a mirror image thereof.
